UNITED STATES PATENT OFFICE.

WILLIAM ZWEIGENBAUM, OF BROOKLYN, NEW YORK.

CUFF HOLDER.

Application filed March 9, 1926. Serial No. 93,357.

My invention relates to cuff holders of the type in which there are two button-like members, one for each end of the cuff, so constructed and arranged that these two members can be brought together and detachably secured by means of a snap fastener.

My invention further contemplates a two-part cuff fastener of the general type just mentioned, but in which the two parts, when detached from each other, may be used for holding the ends of the cuff upon the upper portion of the shirt sleeve of the wearer, or in other words for holding the shirt sleeve folded back and thereby virtually shortened, one or both of the ends of the cuff being held directly in engagement with the upper portion of the sleeve.

In addition, my invention comprehends improvements whereby the cuff holder is readily improved in efficiency, as hereinafter more particularly set forth.

Reference is made to the accompanying drawing forming a part of this specification, and in which like reference characters indicate like parts throughout the several figures.

Figure 1 is a substantially central section through my improved cuff holder, in its assembled form.

Figure 2 shows my device with its various parts practically disassembled.

Figure 3 is a section on the line 3-3 of Figure 1, looking in the direction indicated by the arrows.

Figure 4 is a plan view of a sliding block forming a part of my device.

Figure 5 is a plan view of a slide casing for containing the sliding block just mentioned.

Figure 6 is a side elevation of my device.

Figure 7 is an end elevation thereof.

Figure 8 is a side elevation of the same, but shows the two principal parts of the device as separated.

Figure 9 is a perspective, showing my device as used to hold a sleeve as folded back.

A slide casing 9, having generally the form of a rectangular box is provided at its ends with holes 10, 11 as indicated in Figure 1. It is also provided, at its top, with a somewhat larger hole 12, this hole being displaced a little from the center of the box, as indicated in Figure 5.

Neatly fitted within the slide casing 9 is

a sliding block 13, provided with a cavity 14, this cavity having an extending portion 15 in the form of an undercut, as indicated in Figures 1 and 4. The sliding block 13 carries a pair of pintles 17, 18, provided with heads 19 and 20, and the pinte 17 is encircled by a compression spring 16. With the various parts in position, as indicated in Figure 1, the spring 16 presses the slide casing 9 and the sliding block 13 in opposite directions.

The slide casing 9 carries a screw 21 and a number of rounded teeth 22. Mating the screw 21 is a stem 23, having a substantially cylindrical form and threaded internally, this stem being carried by a gripping plate 24, the latter being provided with rounded teeth 25. The gripping plate 24 is provided with teeth 26. A lever 27 is used in connection with the gripping plate 24, and is provided with a jaw 28, having teeth 29 mating the teeth 26. The jaw 28 has in this instance an ornamental form. The lever 27 is provided with a pair of ears 30, and the gripping plate 24 is provided with a pair of ears 31. A pivot pin 32 extends through the ears 30 and 31 as indicated in Figure 3, and encircling this pivot pin is a torsion spring 33. This torsion spring tends to force the teeth 29 toward or against the teeth 26 when the parts are in the position indicated in Figure 6.

A locking plate 34 is provided with a knob 35 projecting from it, and with a screw 36 which may be integral with it. The locking plate 34 is further provided with a number of rounded teeth 37. Mating the screw 36 is a substantially cylindrical stem 38, threaded internally to fit this screw. The stem 38 is carried by a gripping plate 39, provided with teeth 41 and 40, the teeth 40 being few in number and of rounded form like the teeth 37. A lever 42 is provided with a jaw 43 of ornamental form and provided with teeth 44, which mate the teeth 41. The gripping plate 39 and lever 42 are provided with ears 45, 46, which are connected together by a pivot pin 47, similar to the pivot pin 32 above described, these parts being otherwise connected as indicated in Figure 3.

A shirt sleeve is shown at 48, and mounted upon it by aid of my invention is a cuff 49.

My improved cuff holder, considered with reference to its normal or everyday uses, is properly considered as made of two parts

as shown in Figure 8, these two parts being essentially the two portions of a snap fastener. In order to secure these two parts together, or in other words to close the snap fastener, the locking plate 34 is brought into close proximity with the slide casing 9, the knob 35 being passed down through the hole 12 and into the cavity 14. To facilitate this step, the operator can press with his finger or thumb against the head 20, thus compressing the spring 16 and moving the sliding block 13 a little, relatively to the slide casing 9. This enables the knob 35 to snap into position, so that it extends out into and fills the undercut 15. This locks together the two principal parts of my device, and thus locked they cannot be separated except by the operator again pressing upon the head 20. If for any reason, such for instance as undue wear upon the spring 16 resulting in its becoming weak, the sliding block 13 does not move sufficiently to enable the knob 35 to fit neatly into the undercut 15, the operator by pressing upon the head 17 and instantly bring the parts into proper adjustment.

As regards the manner of fastening the two principal parts shown in Figure 8 upon the ends of a cuff, the procedure is essentially the same for each of the two parts, and therefore I will describe it for only one. The gripping plate 39 is by hand rotated relatively to the locking plate 34 so as to disconnect the screw 36 from the stem 38. The stem 38 is then extended through the proper button hole or button holes of the cuff alone, if the cuff is permanently secured to the shirt sleeve, or to the cuff and wrist-band if the cuff is separate from the sleeve, as the case may be. This done, the screw 36 is inserted into the stem 38, and the gripping plate 39 is thereupon turned relatively to the locking plate 34 until the stem 38 jams firmly against the locking plate.

To take off the cuff holder the process is reversed, the gripping plate 39 being turned relatively to the locking plate 34 until the screw 36 is disconnected from the stem 38. In some instances the two principal parts of my device, shown more particularly in Figure 8, are used for holding the shirt sleeves in folded position, as indicated in Figure 9. For this purpose the two parts of the cuff holder are separated, and each of them is caused to grip the upper portion of the sleeve, near the shoulder thereof. For this purpose the levers 27 and 42 are moved by hand so as to cause the jaws of each pair to move apart, these jaws are placed in position upon the upper portion of the sleeve and allowed to grip the same so as to support the sleeve and cuff as indicated in Figure 9. It will be noted that with the sleeve turned back and supported as just described, the sleeve is not rolled up but rather is folded back. This avoids undue wrinkling

of the sleeve, and also promotes the comfort of the wearer and improves the general appearance of the sleeve and cuff.

By the use of the screws 31 and 26 and hollow stems 23 and 38 mating the same, the cuff holder is secured very firmly in position relatively to the cuff, and this purpose is facilitated by use of the rounded teeth 22, 25, 37 and 40.

The cuff holder as a whole is rendered more efficient in holding together the two ends of the cuff, by reason of the fact that the knob 35 cannot be easily pulled out of place when the parts are in position indicated in Figure 1.

I do not limit myself to the precise construction shown as variations may be made therein without departing from my invention, the scope of which is commensurate with my claim.

Having thus described my invention, what I claim as new and desire to secure by Letters Patent is as follows:

1. In a cuff holder the combination, with two separate parts provided with means whereby they may be mounted upon the ends of a cuff and also provided with means whereby they may be detachably secured together, of a gripping device carried by one of said parts for securing the same to a sleeve, in order to anchor said cuff upon some transient part of the sleeve when the sleeve is folded back upon itself.

2. In a cuff holder the combination, with two separate parts provided with means whereby they may be mounted upon the ends of a cuff and also provided with means whereby they may be detachably connected together, of a pair of gripping members one mounted upon each of said separable parts, to secure said parts to a sleeve when said sleeve is folded back upon itself.

3. In a cuff holder the combination of a pair of separate members to be connected with the respective ends of the cuff, one of said members being provided with a knob, a slide casing carried by the other of said members and provided with an opening to receive said knob, a block slidably mounted within said slide casing and provided with a cavity and with an undercut into which said cavity merges, said block coacting with said slide casing to hold said knob and thus to secure said separate members detachably together.

4. In a cuff holder the combination of a pair of separate members to be connected to the respective ends of the cuff, one of said members being provided with a knob, a slide casing carried by the other of said members and provided with an opening to receive said knob, a block slidably mounted within said slide casing and provided with a cavity and with an undercut merging into said cavity, and a spring mounted within

said slide casing for the purpose of pressing said block into a predetermined position relatively to said slide casing, in order to grip said knob.

5. In a cuff holder, a pair of separable members provided with means for detachably securing them together in order to hold together the ends of a cuff, each of said members comprising two parts screwed together and provided with teeth for holding the end of a cuff.

6. In a cuff holder a pair of separable members provided with means for detachably securing them together in order to connect the ends of a cuff, each of said members comprising two parts having teeth for engaging the end of a cuff, one of said last

mentioned parts being provided with a stem for extending through the end of a cuff, and the other of said parts having means for 20 detachably securing it to said stem.

7. In a cuff holder a pair of separable members each provided with means for holding it upon the end of a cuff, said members being provided with snap fastener mechanism for detachably securing them together, and one of said members being further provided with mechanism movable by hand independently of the other of said members, for actuating said snap fastener mechanism. 25

Signed at Brooklyn, in the county of Kings and State of New York, this 6th day of March, 1926.

WILLIAM ZWEIGENBAUM.
